(57) **CLAIM**

We claim the ornamental design for a face shield, as shown and described.

DESCRIPTION

FIG. 1 is a right perspective view of a face shield showing our design;

FIG. 2 is a left perspective view thereof;

FIG. 3 is a bottom perspective view thereof; and,

FIG. 4 a top perspective view thereof.

The broken lines in FIG. 1 are included for the purpose of illustrating environmental elements that form no part of the claimed design.

The finer lines in FIG. 2 represent those portions of the claimed design that are viewable through the clear material when viewed from this angle.
